UNITED STATES PATENT OFFICE.

CHARLES MATTHEWS MANLY, OF FREEPORT, NEW YORK.

CYLINDER CONSTRUCTION FOR PUMPS OR MOTORS.

1,112,633.

Specification of Letters Patent.

Patented Oct. 6, 1914.

Application filed October 21, 1912. Serial No. 726,993.

To all whom it may concern:

Be it known that I, CHARLES M. MANLY, a citizen of the United States, residing at Freeport, Long Island, New York, have invented a new and useful Improvement in Cylinder Construction for Pumps or Motors, of which the following is a specification.

This invention relates to cylinder constructions for pumps or motors, and particularly to that type of pump and motor disclosed in my pending application No. 639,464 for hydraulic variable speed gear, filed July 19, 1911. As shown in the said application, the variable speed gear comprises a radial stationary cylinder pump and a radial stationary cylinder motor, the two being connected by an intermediate "manifold" comprising two concentric passages constituting the pressure and exhaust sides of the fluid circuit of the speed gear, each passage being connected to the valve chambers of all the pump cylinders and all the motor cylinders by bolted flanged connections. This construction, while quite satisfactory in use, is open to the objection that the manifold casting is a difficult and expensive one to make, and also that it adds considerably to the expense of assembling the machine, because of the large number of bolts to be set, there being five cylinders to each pump and motor, with two connections for each cylinder and at least four bolts to each connection,—a total of not less than eighty bolts.

My present invention has for its object to simplify the construction in this particular and at the same time provide a stronger and cheaper design which occupies less space and can more readily adapt itself for separation of the two elements forming the variable speed gear.

In the accompanying drawings wherein I have illustrated my improvements, Figure 1 is an end view partly in section of the cylinder structure of the motor; Fig. 2 is a vertical section on the median line of Fig. 1, down to the center of the crank chamber; Fig. 3 is a sectional detail view which will be later described.

Referring now to the drawings, in which like reference characters designate like parts throughout the several views, 1 represents the crank casing which is preferably a casting, and which is provided with five circumferentially disposed openings 2 for re-

ceiving the threaded lower ends of the cylinders 4. The casting 1 is machined off around the openings 2 to form tangential seats or shoulders for the collars 5 formed on the cylinders above the threaded ends 3. The nut 6 is threaded on the end of the cylinder within the crank casing, and when screwed in place clamps the collar 5 hard against its seat, forming a substantially rigid joint between the cylinder and the crank chamber.

As explained in my previous application above referred to, the cylinders of the pump and motor are preferably made from drop-forgings of steel, to better withstand the high pressure of the fluid in the gear, and formed in the same forging with each of the cylinders 4 is its valve chamber 7 connected to the cylinders by an intermediate web 8 through which a fluid transmitting passage 9 is formed. In the motor element of the speed gear the portion of the crank chamber to which the motor cylinders are connected is of a larger diameter than the portion to which the valve chambers are attached, and as the passage 9 connects the top of the cylinder with the middle portion of the valve chamber, unless the valve chamber is made excessively long, the passage 9 must be curved downwardly from the top of the cylinder.

In constructing the cylinder and its valve chamber from the solid forging, it is customary to have the web 8 straight and perpendicular to the portions of the forging, forming the cylinder and valve chamber, and then to first bore the cylinder and valve chamber to the diameter desired, and to then bore the passage 9 through the outer wall 9 of the cylinder and the web 8. After the passage is bored, the metal of the web is heated so that the cylinder may be displaced outwardly to a sufficient distance to accommodate the larger portion of the crank casing. It is to be understood that the construction embodies five cylinders 4, radial to a common center and each having a piston connected to a common crank pin, not shown, whereby the pistons are successively reciprocated when actuated by a constant delivery of fluid under pressure. In order to permit the fluid from the pump to reach all the cylinders for the successive operation of their pistons, and for the fluid from the motor cylinders to be returned to the pump, I provide means for connecting all the outer ports

10 of the valve chambers and all the inner ports 11 in a similar manner, to form common intake and delivery ports for all the motor cylinders, the valve chambers being counterbored, as shown particularly in Fig. 2, at the points of connection, to permit free passage of fluid from one valve chamber to another. For making such connections I provide each of the valve chambers with integral ears 12 and 13, one on each side for the upper connections, and similar ears, 14 and 15 for the connections between the ports 11. Into each of the ears 12, 13, 14 and 15 a hole 16 of suitable size is bored at an angle 15 of 54 degrees to the radial center of the valve chamber and connecting with the counterbored ports 10 and 11. Each of the holes 16 is provided with a tapered counterbore, as shown in Fig. 1, to form a seat for the correspondingly tapered end of the pipe or tubing forming the connection between the valve chambers, as will now be described.

I have shown several different forms of intermediate connections between the various valve chambers. At the lower right and left hand sides of Fig. 1 I have shown the connections as separate tubing 17, which is preferably drawn steel tubing of a somewhat resilient nature. At the bottom of Fig. 1 and at the upper right hand corner I have shown the connections as provided with suitable means for the attachment of the pipes from the pump. The connections here shown are preferably formed from a single drop-forging of the shape shown, the passages between the valve chambers being bored therethrough. Into each of the passages a hole is bored from the outside and around the hole the forging is machined to form a flange 18 for the attachment of the flanged couplings of the pipes from the pump, the two flanges being preferably connected by an integral web to prevent rotation of the tubes in their sockets, due to vibration or the strain on the connecting pipes. Between the valve chambers at the upper left hand corner I have shown the two pipes as formed from a single forging connected by an intermediate web in which is formed the bore 19 for a safety valve such as shown in my prior application above referred to for permitting interconnection between the two sides of the circuit of excessive pressure in either side. In forming this portion of the connections a solid forging is bored through to form the pipes or tubes with the tapered ends; then the intermediate web is bored transversely to the tubes and counterbored as shown in Fig. 3. Radial passages 20, 21 are then bored from the outside and inside of the forging, intersecting the outer and inner passages and connecting them with the bore 19 at different points longitudinally thereof. Bores 20, 21 are then closed by plugs to prevent escape of fluid. The forging from

which this piece is made has its outer member straight to facilitate boring, instead of curved, as shown in Fig. 1. After the completion of the work on the forging, and before it is assembled, the outer tube is heated 70 and bent to the shape shown.

In assembling the structure described, the intermediate pipes and forgings are put in place as the valve crank chambers and the connected cylinders are assembled before any 75 of the nuts 6 are screwed in place. Then all the nuts are tightened together so that the tapered sockets for the ends of the pipes and connections are drawn toward each other, the two sockets for each pipe maintaining 80 the same distance from the center during the tightening process, so that the tapered ends of the pipes are forced axially into their sockets without angular displacement. The forcing of the tapered pipe ends into the 85 sockets compresses them uniformly throughout their circumference, making a tight joint all around. The taper of the pipes and sockets is very gradual and consequently the joint will be sufficiently compressed to be 90 tight while still permitting considerable axial movement of the tube and socket before the tube is sufficiently compressed to be ruptured or to offer excessive resistance to the 95 tightening of the nuts. Hence, although the radial movement of each valve chamber effects the tightening of four joints, with this construction no great accuracy is necessary 100 in the length of the tubes or the machining of the sockets because all the joints may be drawn up sufficiently for the valve chamber to be clamped in place even though some are tight before the others.

Having thus described my invention, what I claim as new, and desire to secure by Letters Patent is:—

1. In a pump or motor construction, the combination of a plurality of fluid chambers, fluid transmitting connections between the same, and means for moving said chambers in an angular direction relative to each other to tighten their joints with the fluid transmitting connections.

2. In a pump or motor construction, the combination of a supporting part, a plurality of cylinders detachably connected thereto and extending in different angles therefrom, and a fluid transmitting pipe or tube connecting said cylinders and having tapered ends seated in tapered sockets in the adjacent faces of said cylinders.

3. In a radial cylinder pump or motor construction, the combination of a fluid chamber, cylinders carried by said fluid chamber and held against radial movement relative thereto, and fluid transmitting connections between said cylinders, said connections being held in place by the beforementioned connections for the cylinders.

4. In a radial cylinder pump or motor

- construction, the combination of a central chamber, a plurality of radially extending fluid chambers carried thereby, means for drawing said radial chambers toward the center of said central chamber, an intermediate fluid transmitting connection between said radial chambers having a thrust connection with the same whereby the radial movement of the said chambers tightens the joint between the chambers and the intermediate connection.
5. In a radial cylinder pump or motor construction, the combination of a central chamber having a series of radial bores, a plurality of radial fluid chambers mounted in said bores having collars for engaging the wall of the central chamber around the bore, tapered sockets in the adjacent walls of said chambers, and pipes having tapered ends fitting said bores.
15. In a radial cylinder pump or motor construction, the combination of a crank chamber, a plurality of radially extending fluid chambers carried thereby, a plurality of intermediate fluid transmitting connections between said radial chambers comprising a pair of relatively immovable tubes having thrust connections with said chambers, and means for drawing said chambers inward in a radial direction to tighten the joints between said chambers and said intermediate connections.
25. In a radial cylinder pump or motor construction, the combination of a crank chamber, a plurality of radially extending fluid chambers carried thereby, a plurality of intermediate fluid transmitting connections between said radial chambers comprising a pair of relatively immovable tubes having thrust connections with said chambers, and means for drawing said chambers inward in a radial direction to tighten the joints between said chambers and said intermediate connections.
30. In a radial cylinder pump or motor construction, the combination of a crank chamber, a plurality of radially extending fluid chambers carried thereby, a plurality of intermediate fluid transmitting connections between said radial chambers comprising a single forging consisting of a pair of parallel tubes and an intermediate web having provisions for attachment of fluid connections, said tubes having thrust connections with said chambers, and means for drawing said chambers inward in a radial direction to tighten the joints between said chambers and said intermediate connections.
35. In a radial cylinder pump or motor construction, the combination of a crank chamber, a plurality of radially extending fluid chambers carried thereby, a plurality of intermediate fluid transmitting connections between said radial chambers comprising a single forging consisting of a pair of parallel tubes and an intermediate web forming a valve casing and providing a fluid connection between the parallel tubes, said tubes having thrust connections with said chambers, and means for drawing said chambers inward in a radial direction to tighten the joints between said chambers and said intermediate connections.
40. In a radial cylinder pump or motor construction, the combination of a crank chamber, a plurality of radially extending fluid chambers carried thereby, a plurality of intermediate fluid transmitting connections between said radial chambers comprising a single forging consisting of a pair of parallel tubes and an intermediate web forming a valve casing and providing a fluid connection between the parallel tubes, said tubes having thrust connections with said chambers, and means for drawing said chambers inward in a radial direction to tighten the joints between said chambers and said intermediate connections.
45. In a radial cylinder pump or motor construction, the combination of a crank chamber, a plurality of radially extending fluid chambers carried thereby, a plurality of intermediate fluid transmitting connections between said radial chambers comprising a single forging consisting of a pair of parallel tubes and an intermediate web forming a valve casing and providing a fluid connection between the parallel tubes, said tubes having thrust connections with said chambers, and means for drawing said chambers inward in a radial direction to tighten the joints between said chambers and said intermediate connections.
50. In a radial cylinder pump or motor construction, the combination of a crank chamber, a plurality of radially extending fluid chambers carried thereby, a plurality of intermediate fluid transmitting connections between said radial chambers comprising a single forging consisting of a pair of parallel tubes and an intermediate web forming a valve casing and providing a fluid connection between the parallel tubes, said tubes having thrust connections with said chambers, and means for drawing said chambers inward in a radial direction to tighten the joints between said chambers and said intermediate connections.
55. In a radial cylinder pump or motor construction, the combination of a crank chamber, a plurality of radially extending fluid chambers carried thereby, a plurality of intermediate fluid transmitting connections between said radial chambers comprising a single forging consisting of a pair of parallel tubes and an intermediate web forming a valve casing and providing a fluid connection between the parallel tubes, said tubes having thrust connections with said chambers, and means for drawing said chambers inward in a radial direction to tighten the joints between said chambers and said intermediate connections.
60. In a radial cylinder pump or motor construction, the combination of a crank chamber, a plurality of radially extending fluid chambers carried thereby, a plurality of intermediate fluid transmitting connections between said radial chambers comprising a single forging consisting of a pair of parallel tubes and an intermediate web forming a valve casing and providing a fluid connection between the parallel tubes, said tubes having thrust connections with said chambers, and means for drawing said chambers inward in a radial direction to tighten the joints between said chambers and said intermediate connections.
- In testimony whereof, I, said CHARLES M. MANLY have signed my name to this specification in the presence of two subscribing witnesses, this 19th day of October 1912.
